UNITED STATES PATENT OFFICE.

PHILIP S. HARPER, OF CHICAGO, ILLINOIS.

GAS-RANGE BURNER.

Application filed May 20, 1927. Serial No. 192,852.

This invention relates to gas burners of the type generally used on gas ranges, hot plates and other cooking and heating appliances, and applies solely to a double burner 5 having a plurality of mixing tubes and a similar number of burner sections.

This invention consists of a double gas burner with a single gas cock together with a combination of mixer face and air shutter 10 parts so arranged and constructed as to intercept the area of air supply to each section of the double burner as properly required by such section.

The object of this invention is to provide 15 a simple means of adjusting the air supply for a double type burner.

Another object of this invention is to arrange a burner of this double type so that it may be so constructed as to have only a 20 single movable part for adjustment of the air supply.

Another object of this invention is the provision of a burner of this type which will fit into the space available on the standard 25 gas range.

Another object of this invention is the provision of an air shutter in which a tight joint on the mixer face is insured between said sections and around the opening to the 30 smaller of said sections.

Another object is a shutter for a double burner which may be adjusted without removing the burner from the stove.

These and other objects of this invention 35 will be apparent from the following description and drawings, in which—

Figure 1 is a partial sectional elevation of a burner, air shutter and gas cock of the type of this invention shown in the regularly 40 ly assembled position and taken along line 1—1 of Figure 2;

Figure 2 is a plan view of the entire assembly;

Figure 3 is a bottom view of the stop 45 washer at the lower end of the plug;

Figure 4 is a front elevational view of the mixer face;

Figure 5 is a front view of the inner shutter which lies against the inner side of the 50 mixer face in Figure 1;

Figure 6 is a view of the mixer cap which covers the inner shutter in Figure 1; and

Figure 7 is a front elevational view of the mixer face, the inner shutter and outer 55 cap assembled thereon in an operating position.

Referring now to the drawings, in Figure 1 a manifold pipe 10 is shown into which is screwed one end of the gas cock body 11, said end having a passage 12 therein which continues into the tapered plug 13, said plug having a ground bearing 14 in the said body 11 as in the usual gas cock. The said passage 12 is enlarged at point 15 in said plug and then passes out of the plug into the 60 threaded nozzle end 16 where it is again enlarged at 17 for accommodation of the nozzle jet 18. Said nozzle jet is milled longitudinally so that gas may pass from passage 12 on each side of the said jet. On the 65 threaded nozzle end 16 there is screwed a nozzle cap 21 having in its outer end a centrally placed orifice 22. This jet 18 in combination with the nozzle cap 21, forms an adjustable nozzle, and the cap 21 is screwed 70 more or less on the threads of the nozzle end 16 causing the jet 18 to enter the orifice 22 if conditions require, so as to throttle this orifice.

Returning now to the passage 12, before 75 entering the plug, a smaller passage 23 leads off therefrom into a passage 26 in the casing 11, which passage 26 passes through the plug 13, and is substantially parallel to the former passage 12 of the said plug. Said 80 passage 26 is larger than both the small part and the enlarged part of passage 12 for purposes hereinafter to be set forth.

In the said plug 13 there is a diagonal equalizing passage 32 connecting the passage 26 with the passage 12. From the outer end of passage 26 there leads a connecting passage 33 to an enlarged horizontal passage 34 in the threaded upper nozzle end 35. The outer end of passage 26 is closed 85 by a stopper plug 36 substantially as shown. The said nozzle end 35 is fitted with a jet 37 and cap 38, similar to the lower jet 18 and lower cap 21, except that the orifice 39 in the cap 38 is very much smaller than the former orifice 22 in the cap 21. The lower end of the plug 13 has an extension 40 which extends through a washer 41, a coil spring 42 and a stop washer 43. Said stop washer is held in place by the stop pin 44 which 90 passes transversely through the lower end 40 of the plug 13, and said washer has stops 45 limiting the turning of the plug to substantially 90 degrees. The under surface 46 of said stop washer 43 forms a cam which bears 95 on stop pin 44 and has one or more radial V notches therein engaging said pin in in-

termmediate positions as required between the two 90 degree stop positions. The coil spring 42 is compressed between the washer 41 and the stop washer 43 and serves to 5 maintain said stop washer 43 on its cam surface 46 in bearing against said stop pin 44. The stop washer 43 is guided on the lower end of the casing 11 as shown and has internal ribs (not shown) extending into slots in 10 said casing preventing rotary movement, but said washer is free to slide in said slots in a longitudinal direction.

The head 48 of said plug 13 has a stove bolt 49 threaded therein and serves to fasten 15 on the porcelain handle 50, all in accordance with standard gas range cock practice.

The nozzle caps 21 and 38 project through an outer shutter 51 and an inner shutter 52, said shutters being fastened to the mixer 20 face 53 by the clamping screw 54. Nozzle cap 21 projects into a mixing tube 55 and said mixing tube has side passages 56 leading therefrom into the outer burner section 57 which is of the usual star shape or any 25 other shape desired and has burner ports 58 in the top surface thereof after the manner of the usual construction of gas range burners. The upper nozzle 38 projects into upper mixing tube 59 which in turn leads directly to the boiling burner section 60 which 30 has burner ports 61 in the top thereof. These ports 61 are spaced in a circle or otherwise conveniently arranged to provide a small boiling burner or so called simmer burner.

35 Referring to Figure 4, mixer tubes 55 and 59 are shown separated by division wall 62, which has an enlarged portion 63 with a tapped hole 64 therein. The openings to said mixing tubes 55 and 59 are arranged 40 within a circular wall 65 concentric with the lower mixing tube 55. Figure 5 shows the inner shutter piece 52 which has apertures 66 and 67 to accommodate the caps 21 and 38 shown in Figure 1. It also has an opening 68 registering with the enlarged portion 45 of Figure 4. In addition there are air openings 69 and 70 of width "a" so arranged as to open into the lower mixing tube 55, and there is a slotted opening 71 of width "b" so 50 arranged as to open into upper mixing tube 59.

Figure 6 shows the aforesaid outer mixing cap 51 which has a central hole 72 for the accommodation of lower nozzle cap 21; circularly extending slotted opening 73 of proper width so that upper nozzle 38 may project therethrough and has a small extension 74 of the latter slot 73. In the lower part of said cap are openings 75 and 76. 55 Said latter openings are positioned so that they register with openings 69 and 70 in the mixer shutter, and slot 73 is so placed as to register with slot 71 in said inner shutter.

60 Referring to Figure 7, inner shutter 52 and outer shutter 51 are shown fastened to

the mixer face 53 by means of a clamping screw 54 which passes through circular end of slot 68 in the inner shutter 52 and through extended slot 74 in the outer shutter 51 and screws into tapped hole 64 on the enlarged position or hub 63 which is placed as shown on the division wall 62 between mixing tubes 55 and 59. In Figure 7 the outer shutter is shown partially rotated in a counterclockwise direction so as to partially uncover slot 71 in the inner shutter 52 leading to the upper mixing tube 59 and also partially uncover openings 69 and 70 leading to the lower mixing tube 55. The screw 54 and upper nozzle 38 do not interfere with such rotation since they follow in the circular slotted openings 73 and 74 respectively in said outer shutter. The area of the opening 79 to the simmer section is very small to properly control the air supply to such very small section while openings 80 and 81, two of them together, are large to suit the large section, and in designing a shutter of this type the air opening to the small section is proportioned to the combined openings to the 75 larger section in proportion to the gas properly burned by each. And in this shutter with slotted air openings as shown, if the outer shutter is adjusted for a very small opening first, and then we rotate the outer shutter in counterclockwise direction so as to double the air opening to the small section, it is obvious that the opening to the large section is likewise doubled; and there is always the same proportion between the air 80 opening to the small section and to the large section no matter what the setting of the outer shutter 51. This is substantially as required for proper adjustment of both sections since high gas pressure of a low heating value of gas requiring little air opening affects both sections alike, and the air shutter opening to each section should properly be cut down in area so that the area of air 85 shutter opening is at all times in the same proportion to the gas volume in one section as in the other. Air shutters of the type of this invention are unlikely to be perfectly tight between the face of mixer and the shutters, and while the consequent leakage 90 is not harmful to the large section, it may be on the other hand very harmful to the small section where the primary air is small in amount and the leakage air is of consequently larger proportion thereto. For this reason I have devised this shutter with the clamping screw 54 placed in the wall 62 between the two mixing tubes and consequently 95 it is as close as possible to the opening 82 to the smaller section and clamps the shutters tightly around the edge of this opening. Likewise, I have incorporated a fin 83 at the far side of the opening to decrease the size 100 of this opening, and to keep all parts of the opening as near the clamping screw 54 as 105 110 115 120 125 130

possible. Also in view of the fact that air leakage to the small section is detrimental, I have devised the shutter so that the opening 67 exactly fits the nozzle 38 whereas the 5 openings 66 and 72 are larger than the nozzle 21, and consequently any variation in the spacing of the nozzles on the cock is taken up on the larger section where the leakage, due to the additional opening required for 10 this lower nozzle, does not interfere so seriously with the operation of the burner.

While I have described more or less precisely the details of construction, I do not wish to be understood as limiting myself 15 thereto, as I contemplate changes in form and the proportion of parts and the substitution of equivalents as circumstances suggest or render expedient without departing from the spirit or scope of my invention.

20 I claim:

1. A double gas range burner with a gas cock having a single lever handle and having two gas nozzles, said nozzles projecting through an air shutter common to two mixing tubes into which said nozzles respectively discharge, one to each tube, each of said tubes leading to a burner section having a plurality of burner ports in the upper side thereof, one section having over twice the 25 number of ports as the other section, said air shutter having an adjustable closing means intercepting air openings to both of said mixing tubes, the air opening to one tube being over twice the air opening to the other 30 tube.

2. A double gas range burner with a gas cock having a single plug member intercepting passages leading to two gas nozzles, said nozzles projecting through holes in an 40 air shutter common to the two mixing tubes into which said nozzles respectively discharge, one to each tube, each of said tubes leading to a burner section having a plurality of burner ports in the upper side thereof, one section having over twice the 45 number of ports as the other section, said shutter having an adjustable closing means common to the air openings to the said two mixing tubes, the air opening to one tube being over twice the air opening to the other 50 tube in a plurality of positions of said adjustable closing means.

3. A double gas range burner with a gas cock having a single plug member intercepting passages leading to two gas nozzles, said nozzles projecting through holes in an 55 air shutter common to the two mixing tubes into which said nozzles respectively discharge, one to each tube, each of said tubes leading to a burner section having a plu-

rality of burner ports in the upper side thereof, one section having over twice the number of ports as the other section, said shutter having an adjustable closing means common to the air openings to the said two 65 mixing tubes, the air opening to one tube in a plurality of positions of said adjustable closing means being proportioned to the air opening to the other tube in substantially the same proportion as the ratio between the 70 number of burner ports in one section and the number of burner ports in the other section.

4. A double gas range burner with a gas cock having a single plug member intercepting 75 passages leading to two gas nozzles, said nozzles projecting through holes in an air shutter common to the two mixing tubes into which said nozzles respectively discharge, one to each tube, a wall separating 80 said mixing tubes, a clamping screw threaded into an enlargement contiguous to said wall, each of said tubes leading to a burner section having a plurality of burner ports in the upper side thereof, one section having over twice the 85 number of ports as the other section, said shutter having an adjustable closing means common to the air openings to the said two mixing tubes, the air opening to one tube being over twice the air 90 opening to the other tube in a plurality of positions of said adjustable closing means.

5. A double gas range burner with a gas cock having a single plug member intercepting 95 passages leading to two gas nozzles, said nozzles projecting through holes in an air shutter common to the two mixing tubes into which said nozzles respectively discharge, one to each tube, each of said tubes leading to a burner section having a plurality of 100 burner ports in the upper side thereof, one section having over twice the number of ports as the other section, said shutter having an adjustable closing means common to the air openings to the said two mixing tubes, the air opening to one tube being over twice the air opening to the other tube in a plurality of positions of said adjustable 105 closing means, said shutter being circular in shape with one of the said nozzle holes substantially in the center thereof and the other nozzle hole considerably off center, the nozzle hole in said shutter for the nozzle discharging to the small burner section fitting more closely to the nozzle than the nozzle 110 opening for the nozzle discharging to the large burner section.

Signed at Chicago, Illinois, this 12th day of May, 1927.

PHILIP S. HARPER.
